(57) **CLAIM**

An ornamental design for a pathway light, as shown and described.

DESCRIPTION

FIG. 1 is a perspective view of a pathway light;

FIG. 2 is a bottom view thereof;

FIG. 3 is a top view thereof;

FIG. 4 is a side view thereof;

FIG. 5 is an opposite side view thereof;

FIG. 6 is a front view thereof; and,

FIG. 7 is a rear view thereof.

The portions of the article in broken lines are shown for illustrative purposes only and form no part of the claimed design.
